(57) **CLAIM**

I claim the ornamental design for a sealable wave bag, substantially as shown and described.

DESCRIPTION

FIG. 1 is a front right perspective view of a sealable wave bag showing my new design.

FIG. 2 is a front view of the sealable wave bag of FIG. 1, the rear view being a mirror image thereof.

FIG. 3 is a left side view thereof, the right side view being a mirror image thereof.

FIG. 4 is a top view thereof.

FIG. 5 is a bottom view thereof.

FIG. 6 is an interior view of a rear sheet-like panel, taken along the plane of the line 6-6 in FIG. 3.

FIG. 7 is an interior view of a front sheet-like panel, taken along the plane of the line 7-7 in FIG. 3.

FIG. 8 is a front right perspective view of the sealable wave bag of FIG. 1, illustrating the sealable wave bag in an opened position.

FIG. 9 is a front left perspective view thereof.

FIG. 10 is a front right perspective view of the opened sealable wave bag of FIG. 8, illustrating the opened sealable wave bag with a front handle flap folded down.

FIG. 11 is a front right perspective view of the opened sealable wave bag of FIG. 8, illustrating the opened sealable wave bag with both the front and a rear handle flap folded down.

FIG. 12 is a front right perspective view of the opened sealable wave bag of FIG. 10, illustrating content, shown in dash-dot-dash lines, contained in the opened sealable wave bag, as well as partial removal of a protective cover over an adhesive seal; and,

(Continued)

FIG. 13 is a front right perspective view of the sealable wave bag of FIG. 12, illustrating the front and rear handle flaps sealed together by the adhesive seal at the region generally represented by the two horizontal parallel lines. The dash-dot-dot-dash lines in the Figures show portions of the sealable wave bag which form no part of the claimed design. The dash-dot-dot-dash line showing of content within the sealable wave bag is included for the purpose of illustrating environmental structure and forms no part of the claimed design. The shade lines in the Figures show contours and not surface ornamentation.
